UNITED STATES PATENT OFFICE.

LOUIS E. BALZLEY, OF GLEN RIDGE, NEW JERSEY.

TRAFFIC SIGNAL.

Application filed June 29, 1925. Serial No. 40,338.

This invention relates to the controlling of street traffic, particularly at main intersections.

In systems now in operation, the traffic at street intersections is controlled either manually or automatically by the alternate display of suitable "Stop" and "Go" signals. The change from "Stop" to "Go" conditions and vice versa is sometimes heralded by an intermediate signal indicating that the change from one condition to the other is imminent. With a view to get moving as quickly as possible it has become a quite common practice for the "stopped" line of traffic to start off on the stroke of this intermediate signal without waiting for the signal giving the right of way, which is known to be immediately following. The consequence of this is that frequently the last bit of traffic which had the right of way and which was crossing the intersection when the "change" signal was given, is cut off or hindered in its passage by the oncoming cross line of traffic which started on the "change" signal, prior to actually being given right of way.

This invention has been designed particularly with a view to eliminating such possibilities as those briefly described and with a view to embodying the necessary apparatus in simple, relatively inexpensive and entirely practical form.

The foregoing and other desirable objects are attained by certain novel features of construction, combinations and relations of parts as set forth hereafter.

A particular new feature is the introduction at the end of each clearance period of a traffic stopping signal or instruction positively shutting off traffic in that lane and giving the vehicles still on the way time to cross the intersection before opening the way to the intersecting stream of traffic. This result may be obtained structurally in a number of different ways, several of which are illustrated.

The drawings accompanying and forming part of this specification therefore may be considered as typifying but a few of the many different forms in which the invention may be incorporated.

Figure 1 is a perspective view of the apparatus installed at a street crossing.

Figure 2 is a combined view of the signal arms and the gearing for operating the same as they appear at the end of one of the traffic

periods, just as the signal is about to be switched to stop further traffic in the then open line, without however releasing traffic in the intersecting lane.

Figure 3 is a similar view of the same parts at approximately the end of this intermediate period, with the traffic about to be opened in the intersecting lane.

Figure 4 illustrates the reverse condition from Figure 2 at approximately the end of the cross traffic period.

Figure 5 illustrates the signal again switched to stop the cross traffic without however releasing the first line of traffic.

Figure 6 is a part sectional and part plan view showing particularly the drive gear.

Figure 7 is a broken side elevation of these parts.

Figures 8 and 9 are part sectional, side and plan views of the signal head structure.

Figure 10 is a broken side elevation of a modification wherein the traffic signaling is effected by lights in place of the rotating arms.

Figure 11 is a cross sectional view of the signal head in this form.

Figure 12 is a perspective view of the inner member of the head.

Figure 13 is a partial plan view of the intermittent gearing employed in the operation of this device.

Figure 14 is a partial diagrammatic view of another embodiment wherein the traffic instructions are imparted entirely by flashing lights.

Figure 15 is a plan view of a form of commutator mechanism for controlling the lights.

Figure 16 is a developed plan of the commutator.

In the several forms of the invention herein disclosed, the apparatus is designed for controlling the traffic over two intersecting highways but it will appear as the specification proceeds that the apparatus might be designed for controlling a greater number of intersecting streets. In the illustration the two intersecting ways are designated 1 and 2 respectively and the controller is shown located at the center of the intersection so as to be plainly visible from all sides.

In the first form of the invention, Figures 1 to 9, the signaling is done by two relatively movable units, the first consisting of a set of rectangularly related signal arms 3, 4, 5, 6, radiating from and carried by a hollow

post 7 and a second unit consisting of a set of similarly arranged, but shorter signal arms 8, 9, 10, 11, designed to follow the first set and carried by a tubular post 12, concentric with and surrounding the first post.

These two sets of signal arms are rotated right-handedly in the illustration, a quarter turn at a time and one after the other so that the blades of each alternately cover and 10 uncover the blades of the other. The blades 4 and 6 bear on their front faces, the direction of rotation considered, the clear signals "Go" and the blades 9, 11 of the second unit bear on their rearward faces, corresponding 15 indications so that with the two units as shown in Figures 1 and 2, with the blades 4, 9 and 6, 11 in back to back relation, the "Go" signs will be displayed to traffic on the first roadway. All other sides 20 of the signal arms carry a "Stop" indication, so that under the conditions illustrated the arms 3, 8 and 5, 10 in back to back relation combine to close traffic along the intersecting way 2.

25 At the end of the period decided for traffic along the first way, the inner shaft 7 is rotated a quarter turn to carry the arms of the first unit into the position indicated in Figure 3 where the blades 3 and 5 cover the 30 "Go" indications on the backs of blades 9 and 11 and the "Go" signals on the faces of arms 4 and 6 are carried up in back of the arms 8 and 10 and so are covered thereby.

At this time the signal shows "Stop" in 35 all directions and the period of such indication is calculated of sufficient duration to enable the traffic under way to reach the far side of the intersection and be out of the way of the cross traffic before that starts. Then, 40 at the end of this relatively short "clearance" period, the outer shaft 12 is rotated a quarter turn to the position shown in Figure 4 to cause the arms 8 and 10 to uncover the "Go" signals on the faces of the arms 6 45 and 4, and the "Go" signals on the backs of arms 11 and 9 to appear at the backs of arms 6 and 4. Traffic across the intersection is thereupon opened along the second roadway and continues until the inner shaft 7 50 is next given a quarter turn to bring the "Go" signals on the faces of arms 6 and 4 up against the backs of arms 8 and 10 and to cause the arms 5 and 3 to cover the "Go" signals on the backs of arms 11 and 9, where-

55 upon a momentary "Stop" indication is displayed to all traffic, enabling the last of the lines then under way to clear the intersection before traffic is again opened along the first way.

60 These quarter turns are effected in the present disclosure by a simple set of Geneva gears comprising the smaller slotted gears 13, 14, secured on the lower ends of the shafts 7 and 12 respectively engaged by the 65 larger gears 15, 16 on shaft 17, the latter

carrying the pins 18, 19, for cooperative engagement in the slots 20, 21 in the slotted gears. Shaft 17 is shown as driven continuously by having a worm gear 22 engaged by worm 23 on shaft 24 which in turn carries a 70 worm gear 25 engaged by a worm 26 on the motor shaft 27. This arrangement provides a sufficient reduction in speed to use a constantly running motor. The relation of the pin and slot gears to the signal arms is illustrated in each instance in Figures 2, 3, 4 and 5, the pin 18 of the lower gear being shown in Figure 2 as entering a way in the lower slotted gear 13 to turn the inner shaft 7 after establishing the intermediate clearance 75 period and Figure 3 showing how, slightly later, at the end of this clearance period, pin 19 on the upper gear enters a way in the slotted gear 14 to turn the outer shaft 12 and open the other traffic lane. 80

85 Figures 4 and 5 illustrate a repetition of the two conditions just considered, the first showing the parts at commencement of the intermediate clearance period and the latter, the end of the clearance period with the 90 signals about to be shifted to open the cross lane of traffic.

95 The length of the intermediate or clearance period is determined both by the speed of the parts and the relative circumferential spacing of the pins 18, 19, it being obvious that the further these pins are spaced apart, the longer the intermediate dwell will be and that the closer these pins are together, the shorter such intermediate dwell will be. In 100 the disclosure, the pin gears are shown adjustably fixed on the shaft 17 by set screws 28 so that they may be adjusted rotatably on the shaft for the purpose of varying this period with respect to the travel periods. 105

The signal may be illuminated at night by suitable lighting system. In the illustration one or a number of electric lamps 29 is or are supported over the signal head by a central post 30 extended up through the 110 inner tubular shaft 7, which post also is hollow to accommodate the wiring 31 for the lamps. These lights are shown as protected by a dome 32 also carried by the central post. This dome may be finished inside 115 to act as a reflector.

120 As an additional feature, the dome may be utilized as a housing to cover the signal head at such times that the signal may not be in operation. This additional function is realized in the illustration by lowering the central post to drop the dome down over the signal arms, as indicated in broken lines in Figure 8. The mechanism for effecting the lowering and raising of the dome is 125 shown in Figure 7 as a set of toggle levers 33 operated by a suitably positioned handle 34. This dome raising and lowering mechanism may be connected with the motor circuit so that the motor will be stopped before 130

the dome is lowered and so that the dome will be raised to uncover the signal arms before the motor is started.

In the form of the invention illustrated in Figures 10 to 13 substantially the same results as above are accomplished by means of colored lights or lights showing through colored lenses. In this case the signal head comprises but one rotating unit, a cylindrical shield or mask 35 carried by an intermittently rotating shaft 36 and enclosed within a relatively stationary cylindrical top or cover 37 provided in the four quarters of the same with an upper set of red or "Stop" lenses 38 and a lower set of green or "Go" lenses 39. This stationary outer cover and lens carrier is shown as supported by a post 40 within the tubular shaft 36, said shaft being branched or having brackets 41 at the top for directly supporting the stationary housing and for carrying the upper and lower lamps 42, 43.

As shown in Figure 11, the mask or screen 35 is disposed closely adjacent the inner wall 25 of the lens housing and acts as a "cut-off" for the light, having two diametrically opposite windows 44 in the lower portion for registry with the green lenses and two diametrically opposite peripherally extended windows 45 in the upper portion for registry with the red lenses.

The cut-off screen is turned one-eighth revolution at a time by a constantly rotating gear 46 carrying peripherally spaced pins 47, 48 entering the successive notches 49 in the slotted gear 50 which is secured to the lower end of shaft 36 and is retained by a spring detent 51 engaging the notches. The follower pin 48 is shown as engageable 40 in any one of a series of seats 52 in gear 46 so that the proportionate length of the intermediate clearance period may be varied to suit different requirements.

In the position of the parts shown in Figures 10 to 13 the windows 44 in the cut-off member are in registry with the green lenses 39 which show at the right in Figure 10 and at the left in Figure 11, opening this one lane of traffic, the intersecting lane of traffic being closed off by the registry of the long windows 45 with the upper red lenses 38 which appear at the left in Figure 10 and at the right in Figure 11. As the pin 47 in Figure 13 enters a slot 49 and imparts a one-eighth turn to the mask, the green lenses are cut off by passage of the windows 44 out of registry with lenses 38 and the red lenses are opened by the leading ends of the windows 45 coming into registry with the upper windows 37 appearing at the right in Figure 10 and at the left in Figure 11. Traffic is thus momentarily closed in all directions, enabling that under way to complete passage across the intersection and at the end 65 of this relatively short period the second

pin 48 passes into a succeeding notch 49 and turns the mask another one-eighth revolution, bringing the lower windows 44 into registry with the green lenses for the intersecting lane of traffic, the lens 39 at the left in Figure 10 and that at the right in Figure 11. This last one-eighth revolution leaves the elongated windows 45 in the cut-off still in registry with the right-hand window 38 in Figure 10 and left-hand window 38 in Figure 11, leaving the first considered lane still closed to traffic. On completion of the next movement of gear 46 the first pin 47 turns the cut-off sufficiently to cut off the green lenses and display red signals to the second lane of traffic without however opening the first lane and then when the follower pin 48 imparts the next one-eighth revolution to the screen, at the end of the short clearance period, the first lane is again opened to traffic.

In Figures 14, 15 and 16, apparatus is illustrated by which practically the same results are attained by flashing the lights to give the "Go," the "All stop" and the "Stop" signals respectively. In this instance four red lights 53, 54, 55 and 56 are provided, the opposite ones, 53—55 and 54—56 connected in pairs by wiring 57—58 and 59—60 with brushes 61, 62 bearing on the opposite segments 63, 64 of a commutator 65. These connections receive current from one of the line wires 66, the other side of the line, 67, being connected with a common return brush 68, bearing on the commutator shaft 69, the various segments being connected with said shaft as indicated at 70.

The four green lights 71, 72, 73, 74 are similarly connected in opposite pairs by the two lines of wiring indicated generally at 75 and 76 with the lower rectangularly spaced brushes 77, 78 positioned for cooperation with the oppositely disposed segments 79, 80. The red light segments 63, 64 are of slightly greater than one quarter peripheral extent and the green light segments 79, 80 are to the same extent less than one quarter length, as indicated by the quarter dimensional lines 81 in Figure 16.

The commutator is rotated continuously in the illustration. In the position shown, Figures 14 to 16, the green lights are off and all red lights are on, for the intermediate clearance period. As the trailing edge of segment 63 leaves the brush 61, the red lights 53, 55 are extinguished and simultaneously or substantially so, segment 79 contacts with brush 77 and switches on the green lights 71, 73, opening traffic across the sheet in Figure 14. Meantime the segment 63 remains in contact with brush 62, retaining red lights 54, 56 on and traffic closed vertically of Figure 14. As segment 80 passes from beneath brush 77, green lights 71, 73 are extinguished and at substantially

the same instant, the leading edge of segment 64 reaches the brush 61, cutting in the red lights 53, 55, just before segment 63 leaves brush 62, this providing the "All stop" 5 period for clearance of the traffic under way. As segment 63 leaves brush 62, red lights 54, 56 are extinguished and the segment 80 comes under brush 78 cutting in the green lights 72, 74, opening the traffic vertically 10 of Figure 14. Other methods of switching may be employed to interpose at the end of each clear period, a momentary or short "All stop" period for preventing the to-be-opened line of traffic from cutting off the traffic then 15 under way across the intersection.

It will be obvious from the foregoing that the signal may be controlled or operated either arbitrarily or in a predetermined timed relation and either manually, automatically or semi-automatically. Various structural changes either of a mechanical or an electrical nature may be made, with the accomplishment of the same or equivalent results, such changes all coming within the 20 scope of the following claims. To adapt the signal to various traffic conditions, the same may be mounted on a column at the center of an intersection or be suspended above entirely clear of traffic.

30 What is claimed is:

1. In traffic signaling, a set of stop and go traffic directing signal arms, a second set of stop and go traffic directing signal arms, means for intermittently and alternately 35 partially rotating the two sets of signal arms, both in the same direction with the periods of rest of both sets of equal duration and greater than the periods of movement and with the movement of one set of 40 arms following closely on the movement of the other set of arms.

2. In traffic signaling, a set of rotary signal arms, a set of rotary signal arms arranged to follow the first set and automatic 45 means for intermittently alternately imparting rotary movements always in the same direction to said two sets.

3. In traffic signaling, a set of rotary signal arms, a set of rotary signal arms arranged to follow the first set and means for intermittently alternately rotating said two sets, including intermittent gears operating in recurrent cycles connected respectively 50 with the two sets of signal arms and timed 55 to cause one set of signal arms to quickly follow the movement of the other set and both sets to then dwell the longer period constituting the remainder of the cycle.

4. In traffic signals, a multi-bladed rotary 60 signal unit, means for imparting rotary movements to the same in one direction, traffic starting indicia on the leading faces of only two of the signaling blades and traffic stopping indicia on all other faces 65 of the blades, a second concentrically rotat-

ing multi-bladed signal unit, means for causing the same to intermittently follow the movements of the first, traffic starting indicia on the trailing faces of only two of the blades of said second unit and traffic 70 stopping indicia on all other faces of the blades of said second units.

5. In traffic signals, a multi-bladed rotary signal unit bearing traffic starting indicia on the leading faces of only two of the signaling blades and traffic stopping indicia on all other faces of the blades, a second concentrically rotating multi-bladed signal unit bearing traffic starting indicia on the trailing faces of only two of the blades and traffic stepping indicia on all other faces of the blades and means for repeatedly intermittently alternately rotating said units, both in the same direction including intermittently operated gears connected respectively with the two units.

6. In combination, two sets of relatively rotatable traffic signaling arms and automatic means for alternately intermittently rotating the two sets of arms both in the same direction with one closely following the other to alternately cover and uncover one set of arms by the other set.

7. The combination in a traffic signal including a rotatable signal head having outstanding signal arms, of a dome having a spread to cover said outstanding signal arms and means for lowering said dome into position covering the signal head or for supporting the same in a raised position above 90 and exposing the signal head.

8. The combination in a traffic signal including a rotatable signal head, of a dome, means for lowering said dome into position covering the signal head or for supporting 100 the same in position exposing the signal head and means within the dome for illuminating the signal head when the dome is raised to uncover the signal head.

9. In combination, a rotary head having radiating signaling arms, a second concentric rotary head having radiating signaling arms cooperating with the first signaling arms, a dome and means for raising and lowering the same to uncover and cover said signal heads and for supporting the dome normally in raised position exposing both signal heads.

10. In traffic signals, two sets of concentrically rotating signal arms, both rotating always in the same direction and adapted one to follow the movements of the other so as to alternately cover and uncover the signal indicia of said arms and means for intermittently imparting partial rotary movements alternately to the respective sets of signal arms with the movement of one set of signal arms closely following the movement of the other set.

11. In traffic signals, two sets of concen-

- trically rotating signal arms, both rotat- 15
ing always in the same direction and adapt-
ed one to follow the movements of the other
so as to alternately cover and uncover the
5 signal indicia of said arms and means for
intermittently imparting partial rotary
movements alternately to the respective sets
of signal arms with the movement of one
set of signal arms closely following the
10 movement of the other set, including con-
centrically supported slotted gears each con-
nected with one set of arms and concentri-
cally arranged pin gears having their pins
positioned relatively close together.
12. In traffic signals, concentrically oper- 15
ating relatively rotary signal members, slot-
ted gears connected one with each signal
member, pin gears cooperating with said
slotted gears and arranged to operate first
one and then the other of said signal mem- 20
bers, means for driving said pin gears and
means for variably offsetting the pins of said
pin gears to predeterminedly time the suc-
cessive movements of one signal member in
respect to the other signal member. 25

In witness whereof, I have hereunto set
my hand this 22nd day of June, 1925.

LOUIS E. BALTZLEY.
